Patented Oct. 31, 1922.

INVENTOR
LIONEL A. B. HUTTON.

BY *Lionel A. B. Hutton*

UNITED STATES PATENT OFFICE.

LIONEL ALFRED BENNETT HUTTON, OF CALGARY, ALBERTA, CANADA, ASSIGNOR OF ONE-HALF TO LEOPOLD CLAUDE CONSTABLE, OF MEDICINE HAT, ALBERTA, CANADA.

REENFORCED ANCHORS MADE OF PLASTIC AND SEMIPLASTIC MATERIAL.

Application filed January 8, 1921. Serial No. 435,868.

To all whom it may concern:

Be it known that I, LIONEL ALFRED BENNETT HUTTON, a subject of the King of Great Britain, a resident of the city of 5 Calgary, Province of Alberta, Dominion of Canada, have invented certain new and useful Improvements in Reenforced Anchors Made of Plastic and Semiplastic Material, of which the following is a specification.

10 This invention relates to improvements in reenforced anchors made of plastic and semiplastic material, and the objects of the invention are to provide an anchor which will wedge against the material around it, 15 to offer great resistance that is not liable to be easily overcome, to render the construction simple and not liable to go out of repair, and generally to adapt the same to better perform the functions required of it.

20 With the above and other objects in view, the invention consists essentially of the improved construction particularly described in the following specification and drawings forming part of the same.

25 In the drawings:

Figure 1 is a side elevation of the anchor and rod as seen inserted in the earth.

Figure 2 is a longitudinal section of the wedge shaped anchor of the same.

30 Figure 3 is a cross section on the line 3—3 of Figure 2.

Figure 4 is a longitudinal section of a modified form of anchor.

Figure 5 is a longitudinal section of a 35 further modified form of anchor.

Like characters of reference indicate corresponding parts in all the figures.

Referring to the drawings: A represents 40 an anchor consisting of a conical part 10 and a depending cylindrical portion 11 which is adapted to withstand the strain exerted against it. The anchor can be made of concrete or burned clay or other plastic material.

The anchor is provided in its central part 45 with a hole 13 bored therethrough and having a sleeve 14 of sheet metal inserted therein.

50 A cross-shaped reinforcing member 16 is provided which is designed to be embedded in the concrete casing 10 as approximately the bottom thereof. The reinforcing member 16 has arms 12, the ends of which are turned upwardly as at 17 so that the mem-

ber 16 as a whole is solidly anchored within the concrete anchor 10.

A rod 15 extends within the sleeve and through the reinforcing member 16 bored for that purpose. The rod 15 which is screw threaded at its lower extremity is retained with the member 16 by means of a nut 18 60 threaded on the threaded portion of the rod, and a recess 19 in the bottom surface of the cylindrical portion 11 of the anchor affords room for the nut 18.

The rod 15 is terminated at its upper extremity with an eyelet 20 designed to receive a wire holding the post that is to be anchored or supported.

When in use the anchor is placed in the hole bored in the earth and after the rod 15 70 has been connected to the anchor 10, a few shovelfuls of gravel or crushed rock are thrown in on top of it and the hole is then filled with earth.

Figure 4 illustrates a modification of the 75 invention in which the anchor 10^a is cast in a sheet iron mould 21, which mould is designed to remain thereon permanently and form part of the anchor. The anchor can be cast of any plastic or semi-plastic material.

The anchor is bored at 13^a and has a sleeve 14^a of sheet metal inserted in the hole thus provided. The rod 15 extends within the sleeve 14^a and through the mould 21 bored 85 therefor. The rod is fastened to the anchor by means of the nut 18 threaded to the lower portion of the rod.

A washer 22 is provided on the rods 15, between the nut 18 and the bottoms for the 90 sheet iron mould.

Figure 5 shows another or simpler form of anchor in which the concrete anchor 10 is simply bored at 13 to receive the sleeve 14 adapted to engage the lower portion of the 95 rod 15. A washer 22 is provided at the bottom surface of the anchor and a nut 18 is screwed on the threaded lower portion of the rod to retain the same to the anchor.

As the tension is exerted on the rod by the 100 straightened post, the gravel is forced into the indisturbed earth by the wedge shaped anchor, thus offering great resistance.

As many changes could be made in the 105 above construction and many widely different embodiments of my invention within the

scope of the claims construed without departing from the spirit or scope thereof, it is intended that all matter contained in the accompanying specification and drawings shall be interpreted as illustrative and not in a limiting sense.

What I claim as my invention is:

1. An anchor comprising a conical portion formed with a depending cylindrical base 10 and having a hole bored therethrough, a sleeve of sheet metal in the hole, a reinforcing member embedded in the base, a recess formed in the bottom surface of the base, a rod extending within the sleeve through the 15 reinforcing member, the rod being screw-threaded at its lower end, and a nut located in the recess formed in the bottom of the base and retaining the rod to the reinforcing member.
2. An anchor comprising a conical portion and a depending cylindrical base having a

hole therethrough, a sheet metal sleeve in the hole, a rod formed with an eyelet and extending within the sleeve, a cross-shaped member secured to the anchor, and means securing the rod to the anchor and engaging the cross-shaped member.

3. A concrete anchor comprising a concrete block having a conical upper portion and a cylindrical lower portion, a cross-shaped member formed with upturned outer ends embedded in the cylindrical portion, and a rod passing through the block secured thereto at the lower end and having an eyelet at the upper end.

In witness whereof I have hereunto set my hand in the presence of two witnesses.

LIONEL ALFRED BENNETT HUTTON.

Witnesses:

DAVID LE HOWARD,
EVAN HOLMES GOODFELLOW.
